UNITED STATES PATENT OFFICE.

FRANKLIN A. UMSTED, OF CHICAGO, ILLINOIS.

PURIFYING METHOD AND APPARATUS FOR GAS-MANUFACTURING.

1,332,529

Specification of Letters Patent.

Patented Mar. 2, 1920.

Application filed February 1, 1918. Serial No. 214,863.

To all whom it may concern:

Be it known that I, FRANKLIN A. UMSTED, a citizen of the United States, residing at Chicago, in the county of Cook and State 5 of Illinois, have invented certain new and useful Improvements in Purifying Methods and Apparatus for Gas-Manufacturing, of which the following is a specification.

My invention relates to improvements in 0 low temperature, dry distillation method of manufacturing illuminating, power and industrial gas, and obtaining all of the valuable by-products therefrom together with the improved apparatus for carrying on the 5 manufacture of same.

The primary object of the invention is 0 the provision of a method and improved apparatus for carrying out the method by which I am enabled to utilize waste materials such as garbage, manure, street sweepings, municipal waste such as sewage, peat, saw dust, waste wood, stumps, lignite, low grade sulfurous coals, sugar mill waste, sugar refinery waste, beet and cane sugar 5 pulps and stalks, corn stalks, alfalfa, (green or dry), packing house waste, both animal and vegetable, and in fact any animal or vegetable substances containing sufficient moisture base to give gas upon proper application of heat.

It is a further object of the invention to secure in an improved method and apparatus of the described character greater economy and efficiency in the production of gas and by-products utilizing standard gas making fuels by which I mean the fuels ordinarily employed in the manufacture of lighting and heating gases as well as the materials heretofore referred to.

Other objects of the invention will appear from the following specification which is directed to the preferred embodiment of the invention, the apparatus preferred to be used being depicted in the accompanying drawings of which Figure 1 is a perspective view of a complete system embodying the improved apparatus of the invention. Fig. 2 is a vertical cross sectional view through the retort and regenerating furnace. Figs. 3 to 6 inclusive illustrate my improved purifying apparatus, Fig. 3 being a broken top plan view and Fig. 4 a broken end elevation, while the interior arrangement of the purifier is shown in detail in Figs. 5 and 6, which taken together illustrate a longitudinal vertical sectional view through the puri-

fying apparatus. Fig. 7 is a sectional view illustrating the details of construction of the cooling temperature reducing tank.

In the complete system view Fig. 1, the 60 retort is designated generally by the reference character 10; the purifying apparatus is designated generally by the reference character 40; 60 designates a compressor; 70 a cooling temperature reducing tank. 80 65 is an acid treating tank, 90 is a second compressor and the reference character 100 is applied generally to indicate the final storage 70 gas holder. Before entering upon a detail description of the various units of the system beginning with the retort, it should be 75 stated that the material to be treated for the production of gas and by-products is to be placed in the chamber 11 of the retort 10, in which it is subjected to a gas producing heat 80 but of a somewhat lower temperature than ordinarily employed in the production of gas. The heat in my improved retort is applied to the outside of the heat chamber 85 with the material being treated in the retort chamber. In the details of the connecting pipes or passageways between the units of the system it will be noted that I have followed the approved practice in gas engineering of employing right angular passages where angles are necessary in preference to the curved passages, as it is well known that curved passages tend to clog or collect by-products and sediments. Another 90 advantage of the angular type of connections is that ready access is afforded to angles and connections for the purpose of readily cleaning the pipes and connections, 95 access being had by removing one of the end plates or plugs of the connection. The type 100 of connection referred to is similar throughout the drawings, and is designated by the reference character 12. Gas upon being generated in the retort chamber passes thence through the connection 13 into the 105 purifier 40 where it is treated for the removal of by-products and for purification. This treatment in the purifying device will be described in detail in connection with the consideration of the details of the purifier, it being sufficient to state in the present brief description that in the purifier certain of the by-products will be precipitated in the various compartments of the purifier 110 to be subsequently drawn off while the gas upon leaving the purifier is now in a perfect

state of purification for illuminating purposes. To those skilled in the art it will be understood that I mean by this that the gas is in a state of purification upon leaving the purifier that fits it for maximum efficiency as an illuminant although obviously as is well known illuminating gas contains other valuable by-products which I treat in subsequent portions of the present apparatus to be described.

The purified illuminating gas leaves the purifier 40 through the tubular connecting portions 55, 56, 57, 58, passing thence to the power operated compressor 60, which is of any usual type of construction and is illustrated only diagrammatically in Fig. 1, the power wheel of the compressor being designated by the reference character 61 in the compressor 60. The gas is placed under a higher degree of pressure upon leaving through the duct 62 and passes thence through connections 63, 64 and 65 to the temperature reducing tank 70, where it enters the bottom of this tank through the inlet pipe 65, the outlet of which is raised a sufficient distance above the bottom of the tank to prevent interference with accumulated by-products therein. The tank 70 is preferably of the ordinary construction of sectional lift water seal tank as shown in detail in sectional view Fig. 7. In the cooling tank 70 the compressed gas of illuminating qualities before stated is subjected to the action of the cooling fluids which are contained in closed pipes so that the cooling medium does not come in direct contact with the gas. In cooling tank 70 certain remaining by-products are deposited due to the chilling of the gas upon coming in contact with the cooling tubes. The gaseous portions of the fluid pass thence through ducts 66, 67, 68, 69, 71, 72, 73 and 74 to the reheating chamber or retort 75, which is a closed chamber inclosed within the structure of the retort as shown in Figs. 1 and 2, being so arranged therein as to utilize waste heat currents passing from the fire box surrounding the generating chamber or retort 11. The normal course of the gas after expanded by heat in the reheating chamber 75 is through ducts 76, 77 and 78 into the acid treating tank 80. The latter may be of the general form shown in Fig. 1 divided into compartments in such a manner that all gas entering therein will of necessity pass through an acid bath composed of such acids as will remove all of the remaining by-products that are contained in the gas. For example the form of the tank 80 is divided into two compartments by the plate 81 which projects from the top of the compartment downwardly a short distance from actual contact with the bottom but below normal level of the acid fluid contained within the tank;

thus the acid bath will furnish a liquid seal between the compartments and all gas passing through the inlet duct 78 into the first compartment will pass through the acid bath beneath the plate 81 into the exit chamber, leaving the gas in the state of highest efficiency in British thermal or heat units and adapted for use for industrial and power purposes. By this I mean that at this stage the gas is a fixed or permanent gas and suited for storage or compression in that it will no longer precipitate liquids upon cooling but will remain indefinitely in a dry fluid state and will remain in storage permanently in such condition, also making it in this state suitable for shipment or transportation or storage in portable containers.

The acid bath is designated in the tank 80 by the reference character 82. The precipitated by-products will accumulate upon the top of the acid bath within this tank since they are commonly in the form of oil or greases. Passing from the tank 80 through ducts 83 and 84 the gas enters a second compressor designated generally by the reference character 90 which puts it in condition for final storage and it passes thence through ducts 91 and 92 to the interior of a final storage tank through the discharge pipe 93 shown as having its outlet some distance above the bottom of the tank to assist in the normal circulation of the gas within the final storage holder, the latter being indicated by the reference character 100, and being shown in Fig. 1 as of the ordinary form of water seal sectional gas holder. From the final storage holder 100 the gas will be taken as desired for purposes of distribution as through the outlet duct 105 94, 95.

Obviously the final storage holder may be dispensed with under conditions where it is possible to utilize the gas as fast as produced and coming from the final compressor 90. For example under some conditions a plant of the described character may be utilized to supplement the production of other gas plants or supply mains in which event the gas may be piped directly from the final compressor 90 into such gas mains.

It will be apparent from the above description of my invention that everything taken from the gas after it leaves the purifier 40 will be at the expense of its illuminating qualities. Under some conditions it may be desirable to store or consume the gas in its maximum efficiency as an illuminant in which case I provide the supplementary duct 110 leading directly to the second compressor 90 by tapping into the main supply duct 84 between the acid bath tank 80 and the compressor through which the gas may be shunted around the cooling tank and the reheating and acid bath 133.

apparatus, passing directly into the final storage tank thus avoiding the cooling tank and any precipitation that may take place therein, and also avoiding the reheating and acid bath treatments. The duct 110 is controlled by the valve 111. I also provide another cutoff by which the gas upon leaving the reheating chamber may be shunted around the acid bath compartment 80. This consists of duct 112, leaving the pipe 76 between the reheating chamber and the bath chamber and tapping into the duct 84 between the bath chamber and the second compressor. This supplementary duct is under the control of valve 113, and enables the gas after being reheated to be passed directly through the last compressor and storage holder avoiding the acid bath for the purpose of supplying a gas that is suitable for general domestic purposes, that is, leaving sufficient illuminants in the gas to enable it to be used with a fair degree of satisfaction for illuminating purposes, but at the same time retaining the heat energy of the gas for domestic heating or power or industrial purposes.

In carrying out my improved method of manufacturing gas and removing and conserving the valuable byproducts therefrom I find it essential to employ certain of the units of my improved apparatus as herein described, including the special retorting furnace, the improved purifier, and the improved temperature reducing tank. Before referring more particularly to the method of manufacturing gas the more important units of the apparatus will be described.

The generating and reheating furnace.

The generating furnace or retort and the reheating furnace are preferably combined in the manner illustrated in the perspective view and in the section through this combined apparatus, Fig. 2. Reference has already been made to the closed metallic retort 11 of elongated form having a curved top and sides and a flat bottom and surrounded by a fire chamber on the interior of the walls 10 of the furnace proper which may be of brick or other masonry as shown in Figs. 1 and 2. The retort chamber 11 is permanently closed or sealed throughout except at the feeding end projecting through the outer wall of the furnace and being provided with the removable or detachable member or door 11^a pivotally connected with the supporting member or arm 11^b, which latter is pivoted to the wall of the retort chamber adjacent the mouth thereof as indicated at 11^c. The door may be closed in position to seal the end of the retort 11 by pivoted keeper or clamp 11^d adapted to engage with the free end of the supporting lever 11^b, and being provided with the screw clamp 11^e adapted to engage the free end 11^b of the door sup-

port and press the supporting lever 11^b toward the opening of the chamber in such a manner as to cause the door 11^a to seal the end of the retort chamber whenever it is filled with material adapted to be retorted 70 or reduced to a gaseous condition.

I prefer to construct the retort chamber in such a manner that the fire chamber therein may surround practically the entire body of the retort 11, the latter being supported 75 however at its ends in the front wall of the masonry furnace 10, and also in the rear wall not shown in the drawings. The retorting fire chamber is indicated by the reference character 1, Fig. 2, and the grate bars 80 therein by the reference character 2. The bottom of the firing chamber below the grate is preferably closed by the pan or bottom member 3. There are doors 4 and 5 closing 85 passage ways through the walls of the furnace, these passage ways extending at right angles to the longitudinal diameter of the retort chamber 11. The latter of these passage ways is designed to afford a draft to the furnace beneath the grates and to enable 90 ashes and deposits coming from the grates to be removed. Door 4 closes the ordinary opening for the admission of fuel, and this may also be utilized for the purpose of admitting air currents to the furnace to the extent desired. In order to regulate the 95 action of the retort, the furnace surrounding the retort chamber is spaced from the walls thereof so as to afford a peripheral passage way around the curved upper sides thereof 100 substantially throughout the length of the retort chamber. The reheating chamber 75 is a cylindrical closed chamber having the gas conveyer pipe 74, 76 tapped into the opposite extremities thereof. The chamber 105 75 is also supported near its ends so as to be surrounded by the supplemental walls of the furnace surrounding same. The latter is not provided with grates since this supplemental heating chamber is designed to 110 utilize waste heat currents coming from the generating or retorting furnace 1. This is accomplished by providing one or more ducts 7, 8, and 9 leading out of the retort chamber 1 to a common tortuous passage 115 a, communicating with the three openings 7, 8 and 9, and leading through the communicating passage b into the top of the chamber 6 around cylindrical reheating chamber 75. The opening 6 surrounding 120 the reheating chamber 75 communicates with the vertical flue c in the chimney associated with the retorting and reheating furnace 10, this chimney being of the desired height to conduct away the products of combustion within the firing chamber of the retort and reheating furnace, and to furnish the desired draft to properly operate the apparatus. By arranging the fuel door 4 at the side of the retort furnace and on account 125 130

of the damper controls *d* and *e* for controlling the elongated passage ways around the curved sides of the retort 11, and the damper controls *f*, *g* and *h* in the passages 7, 8 and 9 leading from the retort firing chamber 1, I am enabled to utilize the fuel within the retort chamber to the limit of economy. For example when fuel has been introduced through the door 4 into the fire box 1, and 10 is in a state of combustion at the forward ends of the grates 2, I may by closing the controlling damper *d* and the controls *g* and *h* in the vertical passages 8 and 9 cause the current from the combustible fuel in the 15 retort firing chamber to traverse the bottom side wall and top of the retort chamber 11 in passing from the retort chamber through the vertical opening or flue 7 to the passage way *a* *b* and the reheating chamber and the 20 chimney of the retort plant. If less efficiency is desired from the fuel under the conditions last mentioned the closing of the damper control *e* and the opening of the control *d* will cause the fuel draft to traverse only a comparatively short part of the 25 exterior surface of the retort chamber 11 in passing through the outlets *f*, *a* and *b* to the reheating chamber and chimney thus greatly reducing the efficiency to be obtained from 30 a given quantity of fuel.

The purifying apparatus.

The reference character 40 is applied generally to indicate the purifying apparatus 35 as shown in the system view Fig. 1, the details of this unit being illustrated in Figs. 3 to 6 inclusive. The purifying apparatus consists of a casing of a size to be determined by the capacity of the plant and preferably of substantially the configuration shown in Figs. 3 to 6 inclusive, in which the casing is rectangular in cross section and provided with a plurality of partitions preferably 9 in all dividing the casing into 10 40 intercommunicating chambers all of which are preferably closed to the outside atmosphere. These chambers are designated generally by the reference characters 201 to 210 inclusive, reference characters 201 and 210 45 being applied to the end chambers of the purifier. These end chambers of the purifier compartment are provided near their upper extremities with the inlet and outlet manifolds 211, 212 respectively, the former 50 being adapted to receive the supply main or duct 13 leading from the retort of the generating furnace, while the outlet manifold 212 communicating with the chamber 210 furnishes a convenient means for the attachment 55 of the discharge main or ducts 55, 56 leading to the first compressor 60, or through the shunt pipe direct to the second compressor of the system. The 10 chambers of the purifier may be of substantially the same 60 size and dimensions as illustrated in the

drawings and I prefer to arrange each of the 10 chambers of the purifier with openings in their tops closed by the removal cover plates 213 through which access may be had to the interior of each of the chambers. 70 Screw plugs 214 are also shown closing openings in the cover plates 213, affording limited access to the interior of the chambers by the removal of said plugs. The construction of the bottoms of each of the 75 10 compartments is substantially uniform, there being openings shown through the bottom wall of the purifier casing as shown in Figs. 5 and 6, said openings being closed by plates 215 provided with screw threaded 80 openings for taking the vertically and downwardly extending drawoff pipes or tubes 216, which are screw threaded for engagement with the plates 215. The drawoff pipes 216 are controlled by suitable interposed valve casings 217, having gate valves or other convenient forms of closure members therein and operable from the exterior as indicated at 218, Fig. 4. The purifier casing is divided into the compartments 201 to 210 respectively by division plates of modified construction to adapt the respective compartments for the various functions they are called upon to perform in the operation of purifying the gas passing therethrough. Arranged within the chambers 201 to 205 inclusive and 210 and extending laterally therethrough from side wall to side wall of the purifier casing proper are a plurality of tubular passages 100 219 being secured at their extremities in the end walls of the casing so that they afford open passage ways for cooling fluids such as cold air for example passing from the air intake manifolds 220 to the exhaust air manifolds 221 on the opposite side of the purifier casing common to each of the chambers 201 to 205 inclusive and 210 provided with the said tubular passages. Since chambers 206 to 209 inclusive are not provided with 105 the laterally extending tubular passage ways they are not provided with the intake or exhaust manifolds. While many circulating cooling fluids may be used in operating my improved purifying apparatus, I 110 prefer for economy and efficiency to use cold air which may be taken from the exterior of the building in which the purifier is installed as illustrated in Figs. 3 and 4 in which the extreme reduced ends of the manifolds 220 are shown as protruding on the exterior of the building wall designated by the reference character 222. 223 are circulatory or draft pipes extending from the 115 exhaust manifolds 221. These may be in 120 the form of chimneys or flues passing to the exterior of the building or may be connected to a power operator exhauster for inducing current through the intake manifold, cooling tubes, outlet manifolds and exhaust 125 130

5 pipes or they may usually operate as chimneys, the heated condition of the gases undergoing purification being sufficient to maintain a circulatory draft in the desired direction through the purifying apparatus.

The process and method of operating the system.

10 The material to be retorted is placed in the chamber 11 of the generator or retort and the removable closure or door 11^a is secured in position to hermetically seal the retort except for the outlet pipe 13. Fuel is then introduced in the fire box 1 of the retort through the fuel door 4, to heat the retort and the dry distillation begins. It is an important feature of my improved method that from the time that the materials are retorted until the purified gas is 15 deposited in the final storage holder 100, there is a complete absence of the introduction of moisture in the form of water or vapor to be co-mingled with the gas producing materials or gases generated therefrom in the system. For example it is the common practice in retorting in the manufacture of gas to introduce large quantities of water or vapor into the retort chamber itself and to force the gas through purifiers or scrubbers by jets of moisture in the form 20 of steam all of which is carefully avoided in my improved method and apparatus. The prevailing practice in gas manufacturing is to retort the material co-mingled with moisture or water at a temperature at approximately 2200 to 2800 degrees (Fahr.) This results in the prevailing practice of the use of an abnormally large quantity of fuel to attain the desired temperature for 25 retorting and furthermore such temperatures are unduly destructive resulting in the loss of a large percentage of the material being retorted, whereas in my improved process I prefer to employ temperatures varying from 400 to 600 degrees as the minimum up to 1200 degrees Fahr. as the extreme maximum, according to the quantity of the material being retorted, and in the utilization of such comparatively low temperatures I save a large percentage of the gas generated at the same time securing a 30 thorough degree of distillation because of the fact that water or other moistures are kept out of the retort.

35 I also find by careful tests that by my method of dry distillation in the retort I am enabled to distil with about $\frac{1}{3}$ of the heat units ordinarily required by any other known method of retorting, thereby conserving more than 50 per cent. of the usual fuel requirements. The gas upon being generated and driven from the retort due to the expansion in the retort enters chamber 201 of the purifier through the header 211 near 40 the top of the chamber at a temperature

above 390 degrees Fahr. Passing thence downwardly through the compartment the gas contacts with the exposed surfaces of the cooling pipes 219 in the compartment 201 there being a draft of a cooling fluid passing through these pipes from the intake header 220 to the exhaust header 221. The draft through these headers and the cooling pipes 219 of the compartments of the purifier provided with such cooling pipes may 45 be obtained by the draft flues 223 connected with the exhaust headers 221 or through other suitable draft inducing devices such as suction pumps and the like. The provision by which the intake of the manifolds 220 is 50 on the exterior of the building ordinarily insures the introduction of cold air through the cooling tubes while heat given off in the cooling tubes will tend to rise through draft flues or pipes 223 tending to induce circulation 55 through the cooling flues in the direction indicated by the arrows in Fig. 3. The compartment 201 is without any packing materials or other devices beside the cooling tubes 219 and as the gas contacts with the chilled surface of these tubes in its downward passage through the compartment there results the condensation and removal 60 from the gas of tar or other heavy byproducts such as phenols which will accumulate 65 upon the pipes and be deposited upon the bottom of the compartment to be subsequently drained through the bottom plate 215 and the discharge pipe 216 controlled by gate valve 217. The non-condensed and non-70 precipitated fluid passes from compartment 201 through the opening 230 near the bottom of the division plate 231 between compartments 201 and 202 and entering compartment 202 at a temperature of 320+ degrees 75 to 350+ degrees, (Fahr.) Entering compartment 202 near the bottom thereof the gas will rise through the latter compartment contact with the chilled surface of the tubes 219 therein, removing the creosote, pitch and other heavy oils held in suspension in the gas. There are no packing materials in the compartment 202 and the precipitates will be collected upon the bottom plate 215 to be 80 discharged through the valve and discharge 85 pipes connected therewith as in the case of compartment 201.

85 Unprecipitated gas will rise to the top of compartment 202 and at a temperature of approximately 175+ degrees to 200+ degrees (Fahr.) and pass over the top of the plate 232 between compartments 202 and 203 into the latter compartment, the opening being designated by the reference character 233, Fig. 5. The compartment 203 is 90 constructed similar to the two preceding compartments, being provided with the staggered cooling pipes 219, and as the gas passes downwardly over the cooling surfaces of these pipes medium oils such as turpentine 95

light pitch and kindred products will be condensed and precipitated to be removed from the bottom discharge at pipe 216 as desired. The compartment 203 contains no 5 packing or filtering material aside from the cooling tubes 219. The compartment 203 is divided from the compartment 204 by division plate 234 having the opening 235 near the bottom thereof and through which the 10 gas passes from compartment 203 at a temperature at approximately 140+ degrees to 160+ degrees (Fahr.) into compartment 204.

Compartment 204 is the first of the consecutive compartments provided with packing material. Like the preceding compartments it is provided with a plurality of transverse cooling pipes 219 preferably 11 in all in staggard relation but somewhat more separated, there being three less pipes 20 in this compartment than in the preceding compartments 201 to 203 inclusive. This compartment is separated from compartment 205 by the division plate 236 affording a passage way over the top side of the 25 plate into the compartment 205 so that the gas upon entering the compartment 204 near the bottom through opening 235 will traverse the length of the compartment passing through a packing of water condensate materials such as coke, charcoal, lime 30 or sawdust for the purpose of absorbing and removing water therefrom. Condensation and precipitation of moisture will be obviously expedited by contact also with the 35 surfaces of the air cooled pipes 219. The condensate materials with which this compartment is packed are supported just above the bottom plate 215 to prevent clogging the outlet duct 216 by suitable screen as indicated at 237. After traversing the vertical 40 length of the compartment 204 the gas will pass through the opening at the top of division plate 236 indicated at 238 and will enter the top of compartment 205 at a temperature 45 of approximately 104+ degrees to 114+ degrees, (Fahr.) This compartment contains a still lesser number of cooling tubes 219, 9 in all arranged transversely of the compartment between the inlet and 50 outlet manifolds. The division plate 239 dividing the compartment 205 from its succeeding compartment 206 is provided with an outlet 240 near the bottom so that the gas on entering this compartment at the top 55 traverses the length of the compartment, striking the cooling tubes 219, which latter are submerged in a mixture consisting of equal parts of oxid of iron and sawdust, the oxid of iron being in small granules and the 60 wood being pulverized or in the form of sawdust for the purpose of removing from the gas passing therethrough heavy or concentrated ammonia and kindred products. In this compartment there is a screen arranged some distance above the bottom plate 65

215 as indicated by the reference character 241 for the purpose of holding the purifying materials consisting of oxid of iron and sawdust from mixing with ammonia and kindred products precipitated in this chamber 70 and enabling the precipitations to be drawn off without disturbing the packing material. The free gas leaves the compartment 205 through the opening 240 at a temperature at approximately 98+ degrees to 104+ degrees 75 (Fahr.), entering compartment 206 near the bottom thereof. This compartment is divided from the succeeding compartment 207 by the double wall the first part of which is indicated at 242, and is provided with an 80 opening 243 at the top affording a passage way between this plate 242 and the plate 244 between compartments 206 and 207. This passage way opens at the bottom beneath plate 244 into the compartment 207. 85

In order to simplify the description it may be stated that the remaining compartments 207, 208, 209, 210 respectively are interconnected in the same manner as the compartments 206 and 207 by the staggered 90 plates alternately secured at the bottoms and tops of the compartments and affording downwardly extending passages between the respective compartments. These staggered walls being indicated by the reference characters 245, 246, 247, 248, 249 and 250. The intake into each respective compartment as is the case with compartment 207 being at or near the bottom of the compartment and the outlet at the top. Each of the compartments 206 to 209 inclusive are provided with screens some inches above the bottom of the compartments corresponding to the location of the screen 241 of compartment 205, these screens being designated by the reference 95 characters 251 to 254 respectively. Compartment 206 is loaded solid above the screen 251 with wood, sawdust or finely divided wood particles, but the compartment is not provided with the laterally extending cool 100 ing tubes characteristic of compartments 201 to 205 inclusive, and compartment 210. The purpose of the loading of sawdust, etc., in this compartment is to remove ammonia, heavy naphthalene, and kindred products 105 from the gas. The sawdust loading in this compartment is indicated by the reference character 255. The gas leaves compartment 206 at an approximate temperature of 96+ degrees to 100+ degrees (Fahr.) and passing upwardly through screen 252 into compartment 207 it permeates the loading in this compartment which is also without cooling tubes, and here the balance of ammonia and kindred products are removed and the 110 drying of the gas begun. The loading in this compartment is preferably a stratum of about one half the space above the screen with pulverized lime succeeded by a two inch layer of pebble lime which is lime 115 120 125 130

broken into particles about the size of marbles. The remainder of the compartment above the lime stratum consists of charcoal in the form of pellets the size of 5 hen eggs for the purpose of removing sulfur and kindred products from the gas as it traverses the compartment from the screen to the outlet at the top between the plates 245, 246. From the compartment 207 the 10 gas enters the compartment 208 at a temperature of from 90+ degrees to 95+ degrees (Fahr.), and passes upwardly through a loading of oxid of iron for the purpose of removing the balance of cyanogen gas and 15 sulfur. Leaving the compartment 208 the gas enters compartment 209 packed with an equal mixture of oxid of iron and sawdust to complete the removal of cyanogen and dirt particles. Leaving the compartment 209 at 20 the top the gas at a temperature of approximately 89+ degrees to 92+ degrees (Fahr.) enters the compartment 210 at the bottom thereof. This compartment like the first five compartments of the purifier is provided 25 with a plurality of transverse cooling pipes preferably 9 in all, in staggered relation. This compartment is provided with a screen almost midway between the top and bottom thereof so that three of the transverse 30 cooling pipes 219 are comprised in the space below the screen.

The space below the screen is loaded with a solution of heavy cream of lime. The next two inches above the screen being designated 35 by the reference character 255 is loaded with crushed coke. There is then a layer of two inches of pebbled lime the size of marbles and above this to the top of the compartment a stratum of crushed coke about the 40 size of ordinary marbles. The gas passing upwardly through the cream of lime solution will have the remaining moisture therein removed and the contact with the chilled surfaces and tubes surrounded by the layers of 45 coke and lime will remove any moisture remaining in the gas together with the remaining naphthalene, heavy benzol and kindred products. The gas will pass from the compartment 210 into the manifold 212 at 50 an approximate temperature of 58+ degrees to 64+ degrees, (Fahr.). From the manifold 212 the gas may be piped as hereinafter described direct to a storage holder or to units for further refining and removing benzol and lighter chemical constituents. 55

It should be noted that each of the 10 compartments of the purifier is provided with a drawoff 216 leading from the bottoms thereof and controlled by the gate valve 60 217. The precipitates referred to that collect in the bottoms of each of the respective compartments of the purifier will act as a seal for the outlet ducts 216 so that any of these ducts may be opened at and during the 65 operation of the plant and byproducts re-

moved, care being taken to close the valves when gas begins to escape.

An important feature of the invention is an automatic means for controlling the inlet manifolds supplying cooling fluid to the 70 tubes in compartments 201 to 205 inclusive and compartment 210. Referring to the inlet manifold 220 as shown for example in Fig. 4, it will be seen that the intake 220^a is adapted to be closed by the damper 220^b, 75 the latter being controlled by the reciprocating rod 220^c, connected through stuffing box 220^d with a thermostatic regulator, indicated at 220^e on the interior of one of the compartments of the purifier as for example 80 either of compartments 201 to 205 inclusive and compartment 210, each of such compartments being provided with this thermostatic controller for regulating the admission of the cooling fluid. The purpose of this 85 controller is to keep the temperature within the compartment approximately correct in order to insure precipitation of the various byproducts as enumerated in connection with the operation of these compartments. 90

Another important regulating and safety appliance consists of the gas pilot light indicated at 260, Fig. 4. In each of the compartments there is provided a few inches above the bottom plate of the compartment 95 an outlet duct as designated by the reference character 261, Figs. 5 and 6. The ducts 261 communicate with pipes 262 leading to the pilot lights 260 and are for the purpose of furnishing a constant indicator to the 100 attendant or operator that each of the purifying compartments 201 to 210 respectively are operating properly and are not clogged with an oversupply of byproducts in the bottom of the compartments. For example 105 the outlet ducts 261 are all located approximately at the upper limit of the danger line, and when the accumulation of the byproducts in any given compartment passes the predetermined limit as fixed by the location 110 of the pilot light duct, the precipitated accumulation of byproducts will clog the outlets leading to the pilot light 260 and cut off the supply of illuminant from that compartment. Obviously when the purifier is 115 in operation each of the pilot lights comprising the individual compartments or chambers should be in operation and upon failure of any light to burn for the reasons stated the attendant will be notified that the 120 corresponding compartment needs attention, in order to insure the continuous and satisfactory operation of the plant.

In the side elevation view of the purifier Fig. 4 a supporting structure or metallic 125 frame work and designated by the reference character 270 is shown. This open frame work is desirable in affording convenient access to the lower extremities to the pipes 216 through which byproducts are discharged. 130

It will be seen from the foregoing description of the purifier unit 40 that the gas undergoing treatment within the compartments 201 to 210 respectively will be out of contact as before in the retort from all contact with water or steam resulting in the production by this dry process at the point of exit from the last purifier compartment 210 into the outlet manifold 212 of a gas of the highest illuminating quality. It is well known to those skilled in the art that while gas purified to the degree herein before described in the 10 compartments or chambers of the purifier, is of the highest illuminating standard or quality, it is nevertheless still very rich in benzol and other valuable by-products, and is yet too rich in these by-products to conform to the ordinary standards of a general lighting and heating gas as used in the large municipal plants. My improved system therefore includes a cooling or temperature reducing tank, indicated generally in the Fig. 1 by the reference character 70, and shown in greater detail in sectional view Fig. 7. A suitable power operated compressor is interposed in the piping system between the purifier 40 and the temperature reducing tank 70. The course of the gas upon leaving the discharge manifold 212 of the purifier is through the mains 55 to 58 inclusive to the compressor 60 and from the compressor through the mains 62 to 65 inclusive discharging thence into the interior of the cooling tank 70. This tank 35 may be of the common type of water seal storage tank, modified however with respect to the provision of a special system of cooling pipes in the form of spiral coils as indicated by the reference character 300, the 40 coils of the pipe 300 being supported by the spaced depending members 301, 302 as shown in Fig. 7 arranged to take the pipe coils 300 between them, the coils being suspended by the connecting straps 303. A suitable 45 cooling fluid as brine is circulated through the coils 300 entering the topmost coil of the series through the intake pipe or duct 304 which is connected with the top coil of the series by a flexible tubular connection consisting of the hinge jointed pipe sections 305, 306 respectively. The cooling coil 300 supported by the straps 301, 302, 303 which latter are preferably attached to the movable telescoping section of the tank, 50 is thus adapted to present the considerable cooling surfaces of the coil to the gas within the tank and the circulation of the cooling fluid within the coil is made continuous by the hinged pipe connections leading from the lower loop of the coil to the coil 308 55 which is distributed over the major part of the tank bottom and lies close upon the said bottom serving to cool precipitated byproducts within the tank to be removed therein

from the gas as it is delivered to the tank 70 from the purifier 40 through the compressor 60. The last said flexible connection leading from the coil 300 consists of the hinged pipe connections 307^a, 307 of Fig. 7 which latter is connected through the bottom of the cooling tank with the discharge pipe 309 from the tank. The movable section of the tank 70 carrying the cooling coil may be of the single unit construction shown in Fig. 7, or may be made of a plurality of telescoping sections water sealed with the upper section carrying the cooling devices to insure cooling always at the top of the tank. In Fig. 7 the movable section is designated generally by the reference character 70. The gas upon being delivered from compressor 60 to tank 70 will be chilled and cooled by the apparatus described so that there will be a considerable precipitation of oil and benzol which will accumulate upon the bottom of the tank adjacent the coil 308 whence it may be drawn off through the discharge pipe 310 shown in Fig. 7. The discharge end of the inlet pipe 65 is shown elevated a sufficient distance above the bottom of the tank 70 to prevent the possibility of overflow and stoppage of the inlet by the rise of accumulations of the precipitates in the tank. The same is true of the outlet pipe 66 which communicates with the pipe sections 67, 68, 69, 71, 72, 73 and 74 with the reheating chamber 75 within the retort unit 10 already referred to.

A final storage tank 100 ultimately receives the gas for distribution and use as it comes from the system and a power operated compressor shown diagrammatically in Fig. 1 and indicated by the reference character 90 is adapted to discharge the purified gas of the desired quality through the pipe sections 91, 92 and 93 into the final storage holder 100. The gas entering the final storage holder may be of several different qualities according to the manner in which the system between the purifier 40 and the storage holder 100 is manipulated. For example if it be desired to store gas of the highest illuminating standard or quality as it comes for example from the purifier 40 the bypass main 110 will be opened by manipulation of the valve 111 adjacent the purifier shunting the gas directly to the second compressor 90 and thence to storage tank 100 to be distributed as may be desired through the mains 94, 95. Under such conditions when the valve 111 is opened the compressor 60 should not be operated thus closing main leading to cooling tank 70 and also cutting out the reheating chamber 75 and the acid bath treating tank 80 from the system.

When it is desired, however, to cool and further refine the gas removing the remain-

ing benzol and oils such as nitro-benzene and dinitro-benzene as byproducts it is necessary to pass the gas from cooling tank through the reheating chamber 75 where the gas is 5 expanded by the waste heat from the generating chamber of the retort putting the gas in condition for the production and removal of the nitro and dinitro-benzenes, before being passed through the acid bath of tank 80. 10 The structure of the tank 80 has been described and from which it will be seen that before the gas passes through this tank it will encounter the nitric acid bath, removing the heaviest oils and greases including nitro- 15 benzene and dinitro-benzene which will accumulate upon the top surface of the acid bath within the tank. I prefer to provide discharge pipes in the bottoms of each of the compartments in the bath tank 80, these 20 pipes having their intake ends slightly above the normal level of the bath solution, and outlets at normal level of acid so that accumulating oils and greases may be siphoned from the tank. This is one of the common 25 methods of removing accumulations in acid treating tanks and the discharge pipes are not shown in the tank 80 illustrated in Fig. 1. The gas after being reheated in chamber 75 and passed through the acid bath of tank 30 80 will be of the quality of the ordinary power and industrial gas now being furnished in the larger cities for lighting purposes, but on account of being so thoroughly treated and robbed of its byproducts and 35 illuminants it is only satisfactory for lighting purposes when used with mantles. Such gas however is obviously efficient for all power and industrial purposes including all heating purposes and uses in explosive 40 motors.

In addition to the advantages resulting from the use of my improved method and apparatus such as the employment of extremely low temperature, thus saving fuel 45 and conserving gas which by other methods of distillation and extremely high temperatures is destroyed, I also effect large economies due to the construction of the retorting furnace by which I utilize the waste heat 50 for reheating the gas before passing it through the acid bath. My method of retorting at low temperatures stated is found to result in a saving of about one third of the heat units required by other known methods 55 of retorting and the further absence of the usual introduction of large quantities of water into the system either in the form of liquid or steam, enabling me to conserve a large percentage of the byproducts as well 60 as the explosive or illuminating gases usually destroyed or absorbed by the prevailing methods employing high temperatures and moisture in distillation and refining. Experiments have demonstrated that I save in

my reheating furnace alone by the utilization of the waste heat for the reheating furnace and the low temperatures possible to be employed throughout, about 40% of the fuel over known methods. This surprising economy is also secured by reason of the fact 65 that the furnace is constructed to permit side firing of the distilling unit instead of the prevailing practice of end firing below the retort. A further advantage of the side firing feature of my retort furnace is due 70 to the elimination of danger of explosion which results when the opening to the firing chamber for the introduction of fuel is immediately below the closure for the retort, as it is obvious that upon the opening of the 75 retort gas remaining therein may be ignited upon the opening of the furnace door often with disastrous results due to explosions or fires thus ignited.

I have found that with the improved system as herein shown and described, after the system is in operation and after the generation of the gas has begun in the retort and has spread to the various units of the system, fuel gas for operating the retort 80 furnace may be taken from the supply tank 100 for operation of the retort and that the system will then operate on somewhat less than one fourth of the gas normally produced by the system, leaving over three 85 fourths of the original gas production to remain in storage or to be utilized for commercial purposes and this in addition to the valuable byproducts obtained from the various units of the system as described. 90

Another advantage of my system is in the use of the nitric acid bath in the place of the common sulfuric acid, since the sulfuric acid not only detracts from the quality and quantity of the benzol and kindred oils 105 such as the nitro-benzene and the dinitro-benzene, but it results in detracting from the British thermel heat units of the gas, thus insuring both its lighting and heating values. The nitric acid bath as employed 110 in my system reclaims the benzol and explosives enumerated without the objection stated.

Repeated experiments with my improved process and apparatus demonstrate that the 115 dry process employed results in the production of a permanent fixed gas eliminating the usual 8 to 12% loss by condensation, which is wasted in the gas mains by common manufacturing methods employing moisture 120 or steam in large quantities. The U. S. Government statistics show that the loss by condensation of water manufactured gas is approximately from 8 to 12%. It is an important feature of my improved apparatus 125 and process that the plants may be economically constructed in small units adapted for individual use as on farms or in connection

with small institutions, thus enabling garbage, sewage and other waste products to be reclaimed and made available for light, heat and power purposes.

5 I claim:

1. An apparatus for the manufacture of gas embodying a compartment normally closed to atmosphere, said compartment being divided into a plurality of chambers

10 with intercommunicating tortuous passages between the adjacent chambers, certain of said chambers of the closed compartment having cooling pipes extending laterally between the side walls of the compartment and

15 affording means for the circulation of a cooling fluid through the chambers of the compartments out of contact with gas undergoing purification within the respective chambers, other of said chambers of the

20 compartment being provided with filtering material for the removal of byproducts from the gas undergoing purification in the successive chambers of the compartment, and means for inducing normal flow of gas 25 through the successive chambers of the compartment.

2. An apparatus for use in manufacturing gas embodying a closed compartment having an inlet and outlet for the gaseous fluid, par-

30 titions dividing the said compartment into a plurality of chambers, openings in the said partitions, the openings in each partition constituting an outlet for one compartment and an inlet for its contiguous compartment, 35 the said openings between the compartments being alternately arranged near the top or bottom plates of the compartment whereby the inlet and outlet of each individual chamber will be spaced apart substantially the

40 vertical height of the compartment.

3. An apparatus for use in manufacturing gas embodying a compartment closed to the atmosphere, inlet and outlet pipes for conducting gas to and from the compartment,

45 spaced partitions dividing the said compartment into a plurality of intercommunicating chambers, cooling tubes for permitting the passage of cooling fluid through the chambers of the said compartment out of contact

50 with the gas therein, drawoff pipes connected with each individual chamber of the compartment for the purpose of drawing off precipitates from the respective chambers, and means for indicating on the exterior of the

55 compartment when the accumulated byproducts in the particular chamber should be withdraw to maintain the normal operative condition of the apparatus against clogging.

60 4. An apparatus for use in manufacturing gas embodying a compartment closed to the atmosphere, inlet and outlet pipes conducting gas to and from the compartment, spaced partitions dividing the said compartment into a plurality of intercommunicating

chambers, cooling tubes for permitting the passage of cooling fluid through the chambers of the said compartment out of contact with the gas therein, drawoff pipes connected with each individual chamber of the compartment for the purpose of drawing off precipitates from the respective chambers, and a signaling device to indicate on the exterior of the compartment when the accumulated byproducts in any of the chambers of the compartment have reached a predetermined level that might interfere with the operation of the apparatus, said means comprising an outlet duct or pipe tapped into the wall of each of the chambers of the compartment at the predetermined vertical limit for byproduct accumulations in the chamber bottoms.

5. An apparatus for the purification of gas embodying a closed compartment, there being inlet and outlet passages for gas at the opposite ends of said compartment near the top of the compartment, a plurality of spaced partitions dividing the compartment into a plurality of intercommunicating chambers, the end chambers of the series being connected with the inlet and outlet passages, there being openings in the division plates between the chambers of the compartment, said openings being in staggered relation so that the inlet to each of the chambers of the compartment is near the end of the chamber which is opposite to the end of the compartment near which the outlet is located, and means for introducing a cooling fluid out of contact with the gas in the compartment into a plurality of the chambers of the compartment.

6. In a purifying apparatus for gas the combination with a closed compartment, of inlet and outlet ducts for permitting the circulation of gas through the compartment, means within the compartment for permitting the circulation of cooling fluid through the compartment, the said cooling fluid to be maintained out of contact with gas within the compartment, there being a plurality of intercommunicating chambers in the compartment each of said chambers having spaces at their bottoms for the accumulation of byproducts resulting from the purification of gas, means for draining the said byproducts accumulating spaces, and signaling devices for indicating the height of byproduct accumulations in the respective chambers of the compartment, comprising tubes tapped into the walls of the compartment and communicating with each individual chamber, and lighting devices connected with each of said tubes.

7. In an apparatus for the purification of gas the combination with a closed compartment having inlet and outlet gas passages, division plates for dividing the said compartment into a plurality of intercommuni-

cating chambers, there being openings through the said division plates alternately near the top and bottom portions of the compartment whereby the outlet opening of 5 one chamber constitutes the inlet opening to its adjacent chamber, the inlet and outlet openings of each chamber being located near the respective top and bottom portions of the chamber whereby gas passing through each 10 of the individual chambers will traverse substantially the length of the chamber, and means for drawing byproducts from each of the said chambers.

8. In a purifying apparatus for use in the 15 manufacture of gas the combination with a closed compartment provided with inlet and outlet openings, a plurality of intercommunicating chambers within the compartment, means for introducing cooling fluid 20 into the said chambers out of contact with gas on the interior of the chamber for the purpose of providing cooling surfaces for chilling the gas, means for supplying a cooling fluid, and a thermostatic or heat operating 25 device for controlling the admission of cooling fluid to the said cooling devices of each of the respective chambers of the compartment.

9. In a purifying device for use in the 30 manufacture of gas, the combination with a cooling chamber of a cooling tube extending through said chamber out of contact with gas contained on the interior of the chamber, means for supplying cooling fluid to the said 35 cooling tube, and a thermostatically or heat operated device for controlling the circulation of cooling fluid to the said cooling tube.

10. In a purifying device for use in the manufacture of gas the combination with a 40 closed compartment of substantially rectangular form being divided into a plurality of intercommunicating chambers by spaced partitions, the said spaced partitions having openings so positioned that the outlet 45 to each of the chambers of the compartment is at substantially the end of the chamber opposite to the end at which the intake opening to the said chamber is located, valve controlled drawoff pipes connected with the 50 bottom parts of the chambers of the said compartment, and removable closure plates for the tops of each of the respective chambers of the compartment.

11. In a purifying apparatus for use in the 55 manufacture of gas, the combination of a substantially rectangular compartment divided into a plurality of intercommunicating chambers, valve controlled drawoff pipes for each of said chambers, cooling 60 pipes passing through the chambers of said compartment and being adapted to circulate cooling fluid through said compartment out of contact with gas contained therein in order to present chilled surfaces in contact with the

gas in the compartments, an inlet manifold 65 communicating with the cooling tubes of each individual chamber of the compartment provided with said tubes, means for controlling the admission of cooling fluid into said inlet manifolds, exhaust manifolds 70 communicating with each of the said chambers of the compartment as are provided with the said cooling tubes and inlet manifolds therefor, and means connected with said outlet manifolds for exhausting 75 the cooling fluid therefrom and inducing a circulation of cooling fluid through said manifolds and cooling tubes.

12. A purifying apparatus for use in the manufacture of gas comprising a closed 80 compartment, a plurality of intercommunicating chambers within the said compartment, a portion of said chambers of the compartment being provided with cooling tubes adapted to cause the circulation of a 85 cooling fluid through the respective chambers so provided with tubes out of contact with gas in the said chambers, other of said chambers of the compartment being loaded with purifying materials, screens located in said chambers of the compartment loaded with the said purifying material to maintain space in the bottoms of said compartments for use in the accumulation of byproducts resulting from gas purification, 95 and drawoff pipes valve controlled communicating with the bottoms of the respective chambers of the purifying compartment.

13. A purifying device for use in the manufacture of gas comprising a substantially rectangular compartment divided into a plurality of intercommunicating chambers, valve controlled drawoff pipes in the bottoms of each of the said chambers, gas cooling means in certain of said chambers, 100 gas purifying or filtering means in other of said chambers of the compartment, a chamber within the compartment provided with cooling tubes and loaded with purifying material, and detachable cover plates for the 105 tops of the respective chambers of the purifying compartment.

14. In a purifying device for use in the manufacture of gas the combination with a closed compartment divided into a plurality 110 of intercommunicating chambers, cooling tubes passing laterally between said walls of said chambers for the purpose of permitting the circulation of cooling fluid through the said chambers out of contact with gas on the interior of the chambers for the purpose of precipitating byproducts from the gas to the bottoms of said chambers, and a pilot or warning light connected with the inside of one wall of each compartment adjacent 115 the lowermost of the said cooling tubes within the compartment.

15. In a purifying device for use in the

manufacture of gas the combination with a closed compartment being divided into a plurality of communicating chambers, of cooling tubes connected with certain of said chambers being adapted to present cooling fluids to the interior of said chambers out of contact with the gas contained therein, means for supplying cooling fluid to the said cooling tubes, a thermostatic regulator on the interior of each of said chambers and connections between said thermostatic regulators and said cooling fluid supply.

16. In a purifying device for use in the manufacture of gas the combination with a closed compartment provided with opposed inlet and outlet passages, a plurality of intercommunicating chambers within the said compartment arranged in series between said inlet and outlet passages, cooling and filtering devices for precipitating byproducts from the gas within said intercommunicating chambers, valve controlled drawoff pipes in the bottoms of each of the respective chambers, closure plates in the tops of the respective chambers, and screw threaded closure plugs for temporary access to the interiors of the said chambers located in the said top closure plates.

17. The herein described method of removing by-products from gases which consists in passing gas at a temperature of approximately 390 degrees to 455 degrees Fahr. through a chamber having a plurality of transverse containers or tubes therein, open to the exterior of the chamber and closed to the gas therein, the said tubes or containers having a cooling fluid circulated therethrough and also out of contact with the gas within the chamber for the purpose of precipitating the heavy by-products as tar and phenols, then passing the gas and non-precipitated materials into a second chamber also having a plurality of tubular containers closed to the gas and open to the circulation of a cooling fluid out of contact with the gas in the container whereby the gas at a temperature of approximately 320 degrees to 350 degrees Fahr. will be subjected to the cooling action of the said pipes for the purpose of precipitating creosote, pitch and other heavy oils of a similar character, thence passing the remaining gas and non-precipitated materials into a third chamber at a temperature of approximately 175 to 200 degrees Fahr. provided with transverse tubes closed to the gas in the chamber and being open to the circulation of a cooling fluid whereby the gas within the chamber will be caused to precipitate medium oils as turpentine and light pitch, then passing the remaining gas and non-precipitated materials into a fourth chamber at a temperature of approximately 140 to 160 degrees Fahr., the said fourth chamber being packed with water condensate materials as coke, charcoal,

lime and sawdust for the purpose of precipitating and removing moisture from the gas, then passing the gas into a fifth chamber at a temperature of approximately 104 degrees to 114 degrees Fahr., the said chamber being packed with dry oxid of iron and sawdust for the purpose of removing ammonia, heavy benzol and kindred products from the gas, then passing the remaining gas and non-precipitated materials into a sixth chamber at a temperature of approximately 98 degrees to 104 degrees Fahr. which said chamber is packed with finely divided wood particles or sawdust for the purpose of removing lighter ammonia, heavy naphthalene and kindred products, then passing the remaining gas or non-precipitated materials into a seventh chamber at a temperature of approximately 96 degrees to 100 degrees Fahr., the said chamber being packed with lime and charcoal for the purpose of precipitating the remainder of the ammonia and kindred products and for further drying the gas, then passing the gas at a temperature of approximately 90 degrees to 95 degrees Fahr. into an eighth chamber packed with oxid of iron for the purpose of removing cyanogen gas and sulfur, then passing the remaining gas and non-precipitated materials into a ninth chamber packed with a mixture of oxid of iron and sawdust to complete the removal of cyanogen and sulfur and any dirt particles remaining in the gas, then passing the gas at a temperature of approximately 89 degrees to 92 degrees Fahr. into a tenth chamber packed with lime and crushed coke for the purpose of removing the remainder of the moisture in the gas and any remaining naphthalene, heavy benzol or kindred products, then passing the gas from the purifier at a temperature of approximately 58 degrees to 64 degrees Fahr., the gas then being a fixed gas, to a storage holder or to other apparatus for further refining.

18. The herein described method of removing by-products from gas which consists in passing the gas through suitable containers having tubes therein closed to the interior of the container said tubes having cooling fluids therein for the purpose of removing by-products as tars, phenols, pitch, heavy oils, turpentine and creosote, then submitting the remaining gas and non-precipitated materials to a chamber packed with water condensate materials as coke, charcoal, lime or sawdust for the purpose of removing moisture from the gas, then passing the gas through a container packed with dry oxid of iron and sawdust for the purpose of removing ammonia, heavy naphthalene and kindred products, then passing the non-precipitated gas and remaining materials into a chamber packed with lime and charcoal for the purpose of removing sulfur and kin-

- dred products, then passing the remaining gas and non-precipitated materials through one or more chambers packed with oxid of iron for the purpose of removing any remaining cyanogen gas and sulfur, and finally passing the gas through a chamber packed with lime and coke for the purpose of removing any remaining naphthalene, heavy benzol and kindred products from the gas.
19. In a purifying apparatus for removing by-products from gas, a casing, a plurality of partitions in the casing dividing the interior of the same into a plurality of intercommunicating chambers, means for introducing gases to and removing treated gases from the casing, means for collecting and permitting the removal of precipitated materials from the bottoms of the individual chambers within the casing, there being gas outlets in the walls of each of the said chambers of the casing spaced from the openings in the bottoms of the chambers permitting the removal of the accumulated by-products but so related to the bottoms of the chambers adjacent the by-products discharge openings therein that an abnormal accumulation of by-products within the individual chambers will close the gas outlet in each chamber, and a pilot light or burner connected with each of the said gas outlets for utilizing gas passing therethrough.
20. In a purifying apparatus for removing byproducts from gas, a casing, a plurality of partitions in the casing dividing the interior of the same into a plurality of intercommunicating chambers, means for introducing to and removing treated gases from the casing, means for collecting and permitting the removal of precipitated materials from the bottoms of the individual chambers within the casing, there being a gas outlet in the wall of one of said chambers of the casing spaced from the opening permitting the removal of the accumulated byproducts from the casing, and being so related to the bottom of the chamber that an abnormal accumulation of byproducts therein will close the gas outlet in the chamber, and a pilot light or burner connected with the said gas outlet for utilizing gas passing therethrough, and whereby the light or burner will remain burning as long as normal operation of the chamber is permitted but will extinguish by an accumulation of byproducts above the predetermined position of the gas outlet in the wall of the chamber.
21. In a purifying apparatus for removing byproducts from gas, a casing, a plurality of partitions in the casing dividing the interior of same into a plurality of intercommunicating chambers whereby gas entering one of the chambers may pass through the successive chambers in series, a plurality of transverse tubes in one or more of the chambers adapted to receive the gas at the intake end of the casing, means for introducing a cooling fluid to the interiors of the said cooling tubes out of contact with the gas in the chambers, the said chambers provided with said tubes being without packing material whereby the gas will contact with the tube surfaces, another chamber in the compartment provided with transverse cooling tubes, the last said chamber having the cooling tubes therein covered with granular filtering material, one or more chambers having a portion thereof filled with granular filtering material through which the remaining gas is passed for the purpose of cleaning and removing dirt particles, cyanogen gas, sulfur and other impurities, and a final chamber in the casing into which the remaining gas is introduced, the said final chamber being provided with transverse cooling tubes and a loading of lime through which the gas is forced to pass before leaving the casing for the purpose of removing moisture therefrom.
22. In a purifying apparatus for removing byproducts from gas, a casing, a plurality of partitions in the casing dividing the interior of the same into a plurality of intercommunicating chambers, certain of said chambers being provided with transverse cooling tubes closed to the gas on the interiors of the chambers and open to the reception of a cooling fluid from the exterior of the casing, there being staggered openings between the said chambers and being provided with transverse cooling tubes and packed with filtering material, a plurality of chambers arranged in series following the last said chambers each loaded with a quantity of granular filtering material, the last said chambers being closed against the introduction of cooling fluids, a drying chamber provided with a packing of lime or analogous material for finally drying the gas, and transverse cooling tubes in the last said chamber open to the exterior but closed to the interior of the chamber.
23. In a purifying apparatus for removing byproducts from gas, a casing, a plurality of partitions in the casing dividing the interior of the same into a plurality of intercommunicating chambers, certain of said chambers being provided with transverse cooling tubes closed to the gas on the interiors of the chambers and open to the reception of a cooling fluid from the exterior of the casing, there being staggered openings between the said chambers and being provided with transverse cooling tubes and packed with filtering material, a plurality of chambers arranged in series following the last said chambers each loaded with

a quantity of granular filtering material, the last said chambers being closed against the introduction of cooling fluids, and a drying chamber provided with a packing of 5 lime or analogous material for finally drying the gas.

24. In a purifying apparatus for removing byproducts from gas, comprising a casing divided into a plurality of chambers 10 with intercommunicating passages therebetween whereby gas entering one of the end chambers of the casing may pass through the chambers of the casing in series, transverse cooling tubes in certain of said chambers, 15 said tubes being closed to the interiors of said chambers but open to the exteriors thereof, whereby gas entering said chambers will be caused to contact with exposed surfaces of said tubes for the purpose of 20 removing byproducts as tars, pitch, heavy oils, turpentine and creosote, one or more

chambers in the series being provided with cooling tubes similar to the cooling tubes in the aforesaid chambers but having the exposed surfaces thereof on the interior 25 covered with filtering material for the purpose of removing moisture from the gas, other chambers arranged in series within the casing provided with granular filtering material, the last said chambers being closed 30 against the introduction of cooling tubes or cooling fluids therein for the purpose of removing ammonia, heavy naphthalene, cyanogen gas, sulfur and analogous by-products, and a final chamber packed with 35 lime or other suitable drying material for drying the gas before discharging it from the purifier.

In testimony whereof I have signed my name to this specification on this 25th day 40 of January, A. D. 1918.

FRANKLIN A. UMSTED.
